CHAIN LOCK

Edwin C. Elsner, Glendale, Calif., assignor, by mesne assignments, to Aeroquip Corporation, Jackson, Mich., a corporation of Michigan

Filed Oct. 15, 1956, Ser. No. 615,820

3 Claims. (Cl. 24—116)

This invention relates to a buckle for connecting the ends of a chain or the ends of two separate chains that have their opposite ends anchored, to place tension between said chain ends, whereby the same may be used for anchoring cargo and for similar and comparable purposes.

An object of the present invention is to provide a tension-creating buckle that employs a jack to create desired tension, the buckle being so designed as to enable removal of the jack after the tension is locked by means interconnecting the buckle and one chain end.

Another object of the invention is to provide a buckle of the character referred to in which the jack, after removal as above indicated, may be replaced in operative condition to increase the tension and the increased tension locked as before to enable removal of the jack.

A further object of the invention is to provide a jack-operated buckle that is wholly connected to one chain end of two ends to be connected and uses the other chain end for placing tension between the ends and effecting a releasable lock between the buckle and said other chain end.

The invention is characterized by simplicity and low cost of construction, particularly because the jack that is employed is not a component part of the buckle but is a separate item that may be used on a plurality of buckles, as occasion arises.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes, one embodiment of the present invention, which is given by way of illustration or example only.

In the drawing, like reference characters designate similar parts in the several views.

Fig. 1 is a longitudinal sectional view of a jack-operated buckle according to the present invention.

Fig. 2 is a side view, partly broken away.

Figs. 3, 4 and 5 are cross-sectional views as taken on the respective lines 3—3, 4—4 and 5—5 of Fig. 2.

The chain ends 10 and 11 may be the ends of the same chain or the ends of two separate chains. In either case, the present buckle 12 is connected to chain end 10 and is adapted to be separably connected to chain end 11.

The buckle 12 that is illustrated comprises, generally, a preferably articulated frame 13, means 14 carried by and forming part of said frame to mount a jack 15 for placing tension between chain end 11 and the frame and, therefore, the chain end 10, and means 16 interengaging the means 14 and the chain end 11 to lock the adjusted tension produced by the jack.

2

The buckle frame 13 comprises a cross bar 17 that is here shown as formed by similar plates 18 that are transversely spaced by a member 19. Said plates and member may be weld-connected to impart unity to the cross bar. Intermediate its ends the bar 17 is provided with a bolt 20, the same connecting with the end link of chain end 10, substantially as shown.

The ends of the cross bar are provided with chain-connecting bolts 21, two equal lengths of chain 22 extending from said bolts 21. The flexibility and strength of chain lengths 22 is desired. However, cables or other connecting means may be substituted for chains 22.

The frame 13 is completed by a tubular member 23 which also comprises part of the means 14; as shown, member 23 is provided with opposite studs or the like 24 to which the chains 22 are connected.

In the above manner, the frame 13 defines a space 25 between the chains 22 at the sides and the bar 17 and tubular member 23 at the ends. It will be realized that such a frame would be strong to resist tensile forces applied between chain end 10 and member 23.

The jack 15 per se may be varied and the same may be hydraulically or screw operated, as desired. Regardless how otherwise made, said jack comprises telescopically engaged parts 26 and 27 that are extended or retracted as the jack is operated. In this case, the part 26 is provided with a foot 28 designed to have endwise engagement with tubular member 23, the foot being so formed as to provide clearance for chain end 11 when the same is introduced into member 23 and projecting, in part, into the space 25. Accordingly, the jack part 26 is offset with respect to foot 28 to provide the chain clearance above referred to. The other jack part 27 is provided with a preferably rigid bifurcation 29 that is adapted to engage between two links of chain end 11. While shown at an end of jack part 27, the bifurcation 29 may be located at an intermediate part or even at the end most adjacent to the foot end of the jack.

It will be clear that, with the jack contracted and placed with its foot 28 against the member 23 and its bifurcation 29 engaged with a link of chain end 11 or between two connected links, extension of the jack parts 26 and 27, as by introducing hydraulic fluid at 30, will create forces pulling the chain ends 10 and 11 in opposite directions. Thus, the frame 13 will be placed in tension and said frame and jack 15 connect the chain ends.

The means 16 locks this tension-provided connection so that the jack may be removed. Said means 16 comprises a key 31 that is formed to have a bifurcation 32 and is adapted to be inserted transversely through opposite windows or openings 33 formed in the sides of tubular member 23. Said key may be held captive, as by a suitable string or chain, to be available for use when needed. In any case, after the chain end has been tensioned, as above described, the key is applied so the bifurcation is engaged over a chain link that is disposed edgewise to the windows 33 (see Fig. 3), and the next chain link, which is disposed at right angles, will then be transverse to the bifurcation (see Fig. 1). In this initial application of the key, the same will be loose, as can be understood.

The means 16 also includes a locking member which is shown in the form of an externally threaded tube or hollow cylinder 34, the same being engaged with internal threads 35 provided in member 23. The end of tube 34 directed toward the chain end 10 is provided with a knurled flange 36. It will be evident that, after the key 31 is applied, the knurled flange of tube 34 may be manipulated through the openings afforded by the windows 33 to be extended into engagement with the key and

forcing the key into chain-engaging position, as described. The fingers may be used to manipulate the tube 34.

Now that the chain end 11 is effectively connected to the frame 13, the jack 15 may be removed and the applied tension will be maintained.

If an adjustment between the chain ends 10 and 11 is required that is greater than the capacity of extension of the jack, the maximum extension of said jack is first used and the resultant adjustment of the buckle is locked by the means 16. Now, the jack is re-applied in the same manner as before, but with the bifurcation 29 now engaging a part of the chain more remote from the end that was first engaged. Therefore, by using a step-by-step application of tension, as above, an adjustment between the chain ends 10 and 11 may be effected that is substantially longer than the buckle frame 13. This mode of operation may be carried out because the free end of chain 11 merely falls gravitationally out of the line of pull or operation of the buckle.

By making windows 33 of such length that the key 31 may be applied regardless of the adjusted position of chain end 11 with respect to member 23, and providing for proper extension of the jack, any adjustment of the buckle may be key-locked, as above described.

While the foregoing has illustrated and described what is now contemplated to be the best mode of carrying out my invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described my invention, what I claim and desire to secure by Letters Patent is:

1. In a buckle for connecting two chain ends, a tubular member connected to one chain end and having side openings, the other chain end being adapted to pass longitudinally through said member and to be firmly locked against tension at any desired place on the chain, a transverse key applied to the chain through said openings, and an adjustable member carried by the tubular member to engage against the key, said adjustable member being on the end of the tubular member away from the chain end connected thereto.
2. In a buckle according to claim 1, the adjustable member being threadedly connected to the tubular member and the adjustment thereof being effected by finger manipulation through the mentioned openings.
3. In a buckle according to claim 1, the key being formed with a bifurcation to pass over a link of said chain end and to engage against an adjacent link.
